[57] CLAIM

The ornamental design for a bib for use on a baby bottle,
as shown and described.

DESCRIPTION

FIG. 1 is a front, top and side perspective view of the
bib for use on a baby bottle embodying the design of the
present invention;

FIG. 2 is a top plan view thereof;

FIG. 3 is a bottom plan view thereof;

FIG. 4 is a side elevational view thereof, the side oppo-
site being a mirror image of the side shown in FIG. 4;

FIG. 5 is a front end elevational view thereof; and,

FIG. 6 is a rear end elevational view thereof.

FIG. 1.

FIG. 2.

FIG. 6.

FIG. 3.

FIG. 5.

FIG. 4.
